UNITED STATES PATENT OFFICE.

BASIL M. WILKERSON, OF NEW YORK, N. Y.

COMBINED COMB AND BRUSH.

SPECIFICATION forming part of Letters Patent No. 288,534, dated November 13, 1883.

Application filed June 28, 1883. (No model.)

To all whom it may concern:

Be it known that I, BASIL M. WILKERSON, a citizen of the United States, residing in the city of New York and State of New York, have invented certain new and useful Improvements in a Combined Comb and Brush, of which the following is a specification, reference being made to the accompanying drawings, forming part hereof, in which—

10 Figure 1 is a front view, Fig. 2 is a side view, and Fig. 3 is a rear view, of my invention, which will be first fully described hereinafter, and then particularly pointed out in the claim.

15 Referring to the drawings by letter, A represents one end, and B the other, of the solid piece, of any suitable material, which forms the comb and the body or back of the brush, and in referring to them hereinafter the part A 20 will be called the "comb" and the part B the "brush-back." The comb A is provided with teeth D, of any suitable shape and size, and the brush-back B is provided with bristles,

wires, or any other suitable brushing materials, C, set in the back in any suitable manner, and standing out at right angles thereabout to the teeth D of the comb.

In use the comb forms a handle for the brush, and, vice versa, the brush forms a handle for the comb.

The extreme simplicity, effectiveness, cheapness, and durability of my device will be apparent at a glance without further description.

Having thus fully described my invention, what I claim, and desire to secure by Letters Patent of the United States, is—

A comb having a solid end which forms the back of a brush, said brush having bristles or wires extending at right angles to the comb-teeth, as set forth.

Witness my signature.

BASIL M. WILKERSON.
